(57) **CLAIM**

The ornamental design for a lid with variable inner orifice, as shown and described.

DESCRIPTION

The application relates to a lid with a variable inner orifice for use with a container.

FIG. 1 is a top plan view of a lid with variable inner orifice embodying the new design with the hinged lid thereof swung open;

FIG. 2 is a view partially in section of the lid of FIG. 1, said view taken along lines 2—2;

FIG. 3 is a top plan view of the lid with the hinged lid thereof closed; and,

FIG. 4 is a view partially in section of the lid of FIG. 3, said view taken along lines 4—4.

The broken lines showing portions of the lid or portions of a container to which the lid is affixed are environmental only and form no part of the claimed design.
